UNITED STATES PATENT OFFICE.

CHARLES E. LANG, OF LOS ANGELES, CALIFORNIA, ASSIGNOR TO WASSON ENGINEERING & SUPPLY CO., OF PETALUMA, CALIFORNIA, A CORPORATION OF CALIFORNIA.

RETRIEVING-TROLLEY.

1,102,673.

Specification of Letters Patent.

Patented July 7, 1914.

Application filed June 20, 1910. Serial No. 567,990.

To all whom it may concern:

Be it known that I, CHARLES EUGENE LANG, a citizen of the United States, residing at Los Angeles, in the county of Los Angeles and State of California, have invented new and useful Improvements in Retrieving-Trolleys, of which the following is a specification.

This invention is an improvement of the retrieving trolley described in my application, Serial No. 439,878, filed June 22, 1908, for United States patent on retrieving trolley.

The object of this invention is to simplify the construction and improve the operation of the said retrieving trolley, and to make the automatic retraction of the trolley wheel from the wire and also the resetting action more positive and direct. This invention differs specifically from that disclosed in said previous application in the construction and arrangement of the means to change the fulcrum of the trolley springs.

The accompanying drawings illustrate the invention.

Figure 1 is a broken side elevation on a reduced scale of a trolley embodying this invention mounted for operation on a trolley car, a fragment of which is shown. The trolley is shown in normal running position with the trolley wheel against the trolley wire. Fig. 2 is a broken fragmental plan of the invention on an enlarged scale showing the trolley base turned as though the longitudinal axis of the car extended diagonally across the sheet, the trolley foot being swung relative to the base, into the farthest lateral position which is possible for it to reach after the trolley wheel has escaped from the wire. The large arrow indicates the direction in which the car is supposed to be moving and is at the supposed axis of the car. Fig. 3 is a vertical longitudinal mid-section on line x^3-x^5 , Figs. 2, 9, 10 and 11. Parts are shown in the escaped position in solid lines and in the running position in dotted lines. Fig. 4 is a reduced detached fragmental sectional elevation of the trolley foot, with one of the standards and the fulcrum pin supporting link and roller in place and in the position shown in Fig. 3. Fig. 5 is an elevation on said line x^3-x^5 , showing in dotted lines a position to which the trolley pole may have been thrown by the trolley springs when the trolley wheel

escaped from the wire, and showing in solid lines a position down to which the trolley pole, fulcrumed on the tripping fulcrum lever, has been suddenly kicked or thrown by the action of the trolley springs. Fig. 6 is a detail analogous to Fig. 4 showing the tripping and fulcrum lever in the position shown in Fig. 5, with the lower end of the trolley pole in solid and dotted lines corresponding respectively to the solid and dotted positions thereof in Fig. 5. Fig. 7 (Sheet 3) is a view analogous to Figs. 3 and 5 showing the same parts in resting or unlatched position to which they have arrived from the position of Fig. 5. Fig. 8 is a detail analogous to, and on the same scale as Figs. 4 and 6 showing the fulcrum link, the heel, the locking bolt and the latch in the position shown in Fig. 7. Fig. 9 is a fragmental plan on the scale of Figs. 4 and 6, of one-half of the trolley-foot with parts in the latched or operative position corresponding to that shown in dotted lines in Figs. 3 and 4 and in solid lines in Fig. 14. Fig. 10, (Sheet 4) is a plan on a scale somewhat larger than Fig. 9 of the trolley foot and some of the parts carried thereby; some of the parts being broken and others being sectioned on line x^{10} , Fig. 14, (Sheet 3) to show parts that are obscure in other views. Fig. 11 is a sectional elevation from line x^{11} , Fig. 12, looking in the direction of the arrow. Fig. 12 is a sectional elevation on said line x^3-x^5 , Fig. 2, showing the position assumed by the parts while the trolley pole is being pulled down from the resting position of Fig. 7 to the latched position of Figs. 13 and 14. Fig. 13 is a reduced fragmental detail showing the parts in the latched position to which they are tending in Fig. 12. Fig. 14, (Sheet 3) is a sectional elevation on said line x^3-x^5 , showing the position of the parts as the trolley pole, under restraint of the trolley rope, not shown in this view, is allowed to rise slowly toward the trolley wire. Fig. 15 is a reduced detail of some of the parts in the position shown in Fig. 14. The car 1, insulating trolley foundation 2 thereon, trolley pole 3, trolley wheel 4, and trolley wire 5 are of the usual construction. The annular cast metal trolley base 6 is provided with bolt holes 7 to receive bolts 8 by which it is fastened to the trolley foundation 2, and is also provided with a notch 9 and a race-way groove into which said notch 110

opens. The trolley foot 10 is anti-frictionally supported in the base 6 by anti-friction balls 11 which run in the annular race-way grooves 12, 13, in the base and trolley foot, 5 respectively.

The trolley foot is provided with a notch 9' corresponding to the notch 9 and said notches open respectively into the annular grooves 12, 13, so that when the trolley foot 10 is brought into position in the trolley base with the annular grooves 12, 13, registering with each other, and the notches 9, 9' also registering with each other, the anti-friction balls 11 may be inserted into the race-way 15 formed by grooves 12, 13, and will then support the trolley foot in the trolley base. The notches 9 and 9' are arranged in such positions that when the trolley is in operation said notches are not liable to register. In 20 practice the race-way will be appropriately filled with the balls, room being left in the race-way to allow plenty of play, and a sufficient number of balls being supplied to insure a satisfactory distribution of the balls 25 around the race-way. The balls substantially correspond in diameter with the race-way so that there will be a true anti-friction support against all strain in every direction without liability of rattling.

Two standards 14, 14' project upwardly from the trolley foot 10 at the sides thereof, and each is provided with five holes, 15, 16, 17, 18 and 19, in which are fixed pins 24, 30, 39 (39') 41 and 31 respectively. The shank 35 20 of the trolley pole 3 is carried between the standards 14, 14' by means of fulcrum pin supporting links 21, 21', fulcrum stay link 22, fulcrum heel link 23 and fulcrum heel pin 24. The fulcrum heel link 23 is 40 bifurcated and is pivotally mounted by means of the fulcrum heel pin 24 which is supported in the holes 15 of the standards and is provided with a roller 25 to contact a heel 26 on the shank 20 when the trolley pole is at rest as in Fig. 7 or is being moved 45 down to resetting or latching position as in Figs. 12 and 13. The fulcrum pin supporting links 21, 21' are provided with longitudinal slots 27 to carry anti-friction rollers 28, 28' that are journaled on, and that carry the shifting fulcrum pin 29 of the trolley pole shank 20; and said links 21, 21' are swung from hanger pins 30 that are fixed in the holes 16. The stay link 22 is pivoted 50 55 on the stay pin 31 that is fixed in the holes 19 of the standards, and said stay link 22 is provided with a narrow slot 32, registering with a wider slot 33 in the pivoted heel link 23. The fulcrum pin 29 practically fits 60 from side to side of the slot 32 and extends through the slots 32, 33; there being anti-friction rollers 29' on said pin 29 to roll in and practically fit the slot 33.

It is thus seen that, normally, the lower 65 end of the trolley pole is shiftably fulcrumed

by means of the fulcrum pin, the rollers, links, hanger pins and standards upon the trolley foot, and is capable of moving forward and back axially, and up and down in limited paths on the first, or normal shifting 70 fulcrum pin 29, being restrained from too great forward and upward movement by the links 21, 22 and 23.

The trolley spring, which, as with said former application, is composed of two helicals 34, 34' on opposite sides of the trolley pole, is fastened by hook bolts 35 and nuts 36 to the trolley pole arm 37 that projects upward and forward from the trolley shank. Said helicals are engaged at their lower ends 80 with hooks 38, 38' carried by pins 39, 39' mounted in the holes 17 in the standard, there being a hook and a pin therefor upon each standard.

The hanger pins 30 and hook pins 39 are 85 both above the level of the fulcrum pin 29; the heel pin 24 and the stay pin 31; and the force of the trolley spring is effective through the guidance of the links, to move the trolley pole forwardly endwise toward the front of 90 the standards, and the fulcrum pin 29 is restrained from too great forward movement by the links 21, 22 and heel link 23.

The tripping and fulcrum lever 40 is pivoted on a pin 41 that is supported in the 95 holes 18 of the standards 14, 14', which holes are located in front of and above the level of the fulcrum pin 29.

The shank 20 is provided with a smooth face 42 with which the rounded rearward end 43 of the lever 40 contacts, said face 42 and rounded rearward end 43 being in slideable relation to each other so that when the trolley pole moves forward, the lever may in some periods be operated thereby on pivot 41 and at other periods when the lever is held stationary, the trolley pole may be fulcrumed upon said end 43 of the lever 40, said end thus forming the secondary or tripping fulcrum. 110

The heel link 23 is provided with a tip 44 which is rounded at the front and angular at the back and is adapted to contact with the rear free tip 45 of the latch 46, said latch tip being rounded at the back and notched to engage the angular portion of the tip 44 of the heel link. Said latch 46 is pivoted by a pivot 47 to a hanger 48 that extends down from the front of the trolley foot 10; and said latch is normally held resiliently in latching position by the coiled spring 49, the lower end of which is caught on the hook 50 of the latch and the upper end on the hook 51 of the tripping fulcrum lever 40. Said lever 40 projects forward from its pivot 41 and is pivoted by a pivot 52 to a piston rod link 53 that is pivoted by pivot 54 to a shouldered piston rod 55, which is similar to the piston rod shown in my previous application and is provided at its 125 130

lower end with a reduced portion forming a stud 56 on which is secured a recessed and perforated valved piston head 57 having a valve 58. Said piston head is fixed on the 5 piston rod by means of a sleeve-like nut 59, the sleeve 60 of which nut extends into the valve seat recess 61 of the piston head to hold said piston head tightly against the shoulder of the piston rod 55 and also supports a spiral spring 62 which is in the recess 61 and tends to hold the valve 58 depressed against the head of the bolt 59. When the valve 58 is thus depressed it leaves an open way through the perforations 63 of 10 the piston head. Said piston head is mounted in a vertical cylinder 64, the upper end of which is closed by a gland 65 that is provided with a vent pipe 66 having perforations 67 beneath its cap 68 and extending up 15 above the top of the gland so that the cylinder 64 may be filled through the pipe 66, with a suitable liquid as oil when the cap 68 is removed. The interior of the cylinder is open above the piston to external air pressure at all times so that when the valve 58 is 20 open the liquid will flow by gravity to the bottom of the cylinder.

The cylinder 64 has a flexible bottom formed by a diaphragm 69 reinforced by central plates 70 and 71, and the gland or upper cylinder head 65 is held in place by bolts 72 passing through the gland 65 and screwed into the cylinder and said cylinder is fastened to the trolley foot 10 by bolts 73 passing 25 through lugs 74 and through the diaphragm and screwed into the trolley foot, thus to clamp the cylinder, the diaphragm and the trolley foot all tightly together so as to hold the liquid body 75 against the 30 downward pressure of the piston head when such head is acted upon by the piston rod and this occurs whenever the rear end of the lever 40 is acted against by the trolley pole shank 20.

45 The lower reinforcing plate or head 71 under the diaphragm is provided with a stem 76 that moves in a vertical guide 77 formed on the trolley foot 10, and engages a boss 78 on the top of the latch 46 near the 50 pivot 47 of said latch, so that when the piston is suddenly forced down the piston head 57 will overtake the valve 58 which is caught by the liquid body 75 and will close the passage way 63 thus making the piston head 55 practically solid so that upon its further descent it will force the liquid body 75 downward to drive down the diaphragm and consequently the head 71 and its stem 76 to force the latch down to release the tip 44 of the 60 heel, as shown in Fig. 3, so that said tip may swing backward from the latched position shown in Fig. 14 to the positions shown in Figs. 5 and 7, where the diaphragm, liquid and piston form a block for the lever.

65 The trolley pole is provided with the usual

trolley rope 79 by which it may be drawn down in the usual manner to allow the parts to become latched as shown in Figs. 13 and 14.

A locking bolt 80 is pivoted by a pivot 81 to the lower end of the heel link 23, and the trolley base is provided with a number of reversely arranged ratchet teeth 82 and 83 having sloping outer faces 84 and straight inner faces 85; said ratchet teeth being arranged in pairs at front and back of said trolley base and spaced apart from each other sufficiently to allow a limited movement of the trolley foot when the locking bolt 80 is extended between the straight faces 85 as shown in Fig. 5. Said locking bolt is upwardly curved at its tip and is adapted to pass freely over the sloping outer faces of teeth 82 and 83 to enter between the teeth of either pair at front or back but cannot return over the straight inner faces of the teeth so that if the locking bolt is extended when the trolley pole is swung into position at right angles to the car, the trolley pole may be swung around into line with the axis of the car either at front or back and when thus swung will be locked against further lateral movement beyond the certain limit determined by the space between the straight faces of the teeth. Bolt guides 86 extend up from the trolley foot 10, one on each side of said bolt 80 and provide against wrenching of the pivot 81 when the bolt 80 is extended as shown in Fig. 5. A set screw 87 holds the lower end of the trolley pole in the socket of the shank.

In installing the trolley, the dash pot chamber or cylinder 64 is supplied with oil when the trolley pole is raised to its highest position; the piston rod at that time being most deeply inserted into the chamber, so that a surplus of oil cannot be put into the chamber, otherwise the chamber might be filled too full so that when the trolley pole were to swing up oil would be squirted out of the vent tube.

In practical operation when the trolley pole is latched as shown in Figs. 14 and 15, and is restrained by the trolley rope or by the trolley wire so that its up and down movement will be comparatively slow, such as may occur in easing the trolley wheel to the wire or in running along and responding to the undulations of the wire, the valve 58 will be held down by the spring 62 so that the liquid in the cylinder may freely pass through the by-pass formed by the perforations in the piston head; but in case of sudden upward movement of the trolley pole, such as occurs when the trolley wheel leaves the wire, the trolley springs force the trolley shank against the rounded back end 43 of the lever 40, and said lever responding to the thrust, suddenly forces down the head a short distance, thus closing the valve 58 and

forcing down the liquid body, and operating the latch 46, thereby releasing the heel link as shown in Fig. 3. During this sudden upward and forward movement of the trolley pole the tendency of the trolley springs is to force the trolley pole forwardly endwise as well as up and consequently as soon as the heel link tip 44 is released from the latch tip 45, said link tends to swing forward under the pressure of the fulcrum pin 29. As the fulcrum lever 40 is now held rigid against further upward movement of its rear end 43 and since said end 43 contacts with the shank behind the hanger pin 30, the trolley pole can only move forward at its lower end by moving downward at its rear end and consequently the force of the springs 34 coming through the face 42 of the shank on the fulcrum 43 causes the upper end of the trolley pole to be suddenly jerked or kicked down into the position shown in solid lines in Fig. 5. Thence the trolley pole swings down until its heel 26 rests on the heel roller 25. In the meantime the fulcrum pin 29 rises in the slots 27 and 33 while the supporting links 21 swing forward until said pin is stopped as shown in Fig. 7, the leverage of the springs 34 to lift the pole being now insufficient to swing the pole into running position.

To replace the trolley wheel on the wire the operator may now, by the means of the trolley rope 79 pull the pole down from the resting position shown in Fig. 7, whereupon the heel 26 fulcruming on the roller 25 will force the fulcrum pin 29 backward, (see Figs. 7 and 12) thereby increasing the tension of the springs 34, 34'. During this operation the tripping lever 40, released from upward pressure of the trolley pole, will operate under tension of the spring 49 to lift the valved piston head 57, thus relieving the stem 76 from its latch operating pressure and the heel link 23 will swing on the heel pin 24 until its tip 44 comes in front of the hook of the latch 46 whereupon the latch rises under the force of the spring 49 thus latching the tip 44. The tension of the trolley springs 34, 34' is now sufficient to raise the trolley pole as the same is eased up for that purpose from the position shown in Fig. 14, to the position shown in Fig. 1.

I claim:—

1. The combination with a pivoted trolley pole, of a spring to uphold the trolley pole, a normal fulcrum for the trolley pole, said fulcrum being shiftable to increase the tension of the spring on the trolley pole, a latch to hold said fulcrum in the position of increased tension, a fulcrum lever contacting with the trolley pole, rearward from the normal fulcrum of the trolley pole, and means connecting the fulcrum lever and latch; said means operating to release the latch upon sudden movement of the lever and being in-

operative to release the latch upon relatively slow movement of the lever.

2. The combination with a trolley pole, of a fulcrum in one end of the trolley pole, links shiftably supporting and limiting the forward and upward movement of the fulcrum pin, springs to move the trolley pole forwardly endwise and upward, means to hold said links against the force of the spring, a lever contacting with and forming a secondary fulcrum for the trolley pole, and means operatable by sudden upward movement of the lever to release said link holding means, said operatable means being inoperative to release the link holding means upon relatively slow movement of the lever.

3. The combination with a support, of a pin, a link pivoted on the pin and provided below the pin with a tip and above the pin with a vertical slot, a stay link pivoted to the support and extending aslant therefrom to a point above said pin and there provided with a slot registering with the slot in the first named link, a supporting link pivoted to the support and extending downward from its pivot and provided with a slot registering with the slots of the aforesaid links, a fulcrum pin extending through the slots, a trolley pole fulcrumed on the fulcrum pin, a spring pivoted to the support, the pivot thereof lying in a horizontal plane that extends between the horizontal planes of the fulcrum pin and the pivot of the supporting link, said spring being connected to the trolley pole, and adapted to swing with the trolley pole to bring its draft line above the supporting link pivot when the trolley pole is up and below such pivot when the trolley pole is down, thus to reduce the leverage between the spring and the trolley pole when the trolley pole is down and to increase such leverage when the trolley pole is up.

4. The combination with a trolley base, of a trolley pole, a pin supporting the trolley pole, a pivoted link to support the pin, means to move the trolley pole upward and forward, a latch to catch the pivoted link, a lever in slidably engagement with the pole and adapted to be operated thereby as the pole rises, a spring between the lever and the latch to hold the latch in catching position and the lever and pole in engaging position, mechanism between the lever and the latch to release the latch when the lever is operated by the pole and means to limit the upward and forward movement of the pole.

5. The combination with a trolley pole, of a primary fulcrum normally in commission to fulcrum the trolley pole at one end, a spring connected at one end to the trolley pole, means to hold the other end of the spring, means to hold the primary fulcrum in commission, and means including a normally inactive secondary fulcrum to fulcrum the trolley pole intermediate its ends, said

means being only operable by sudden upward movement of the trolley pole to put the primary fulcrum out of commission and the secondary fulcrum into commission.

5 6. The combination with a trolley pole, of a shiftable primary fulcrum normally in commission to fulcrum the trolley pole at one end, a spring connected at one end to the trolley pole, means to hold the other end 10 of the spring, means to hold the primary fulcrum against shifting, and means including a normally inactive secondary fulcrum

to fulcrum the trolley pole intermediate its ends, said means being only operable by sudden upward movement of the trolley pole 10 to release said fulcrum holding means.

In testimony whereof, I have hereunto set my hand at Los Angeles, California, this 13th day of June, 1910.

CHARLES E. LANG.
